PAPERMAKING MACHINE

Irving C. Jennings, South Norwalk, Conn.

Application May 8, 1936, Serial No. 78,704

11 Claims. (Cl. 92—53)

This invention relates to paper making machinery and more particularly to improved suction roll apparatus therefor.

The suction roll as applied to paper machines comprises a perforated cylinder supported on bearings, and suitably driven, such cylinder being interposed in the machine beneath the wet pulp, for the purpose of extracting moisture from the pulp. This is accomplished by providing a stationary box inside the roll and creating suction within the box whereby to draw air through the wet pulp, thereby extracting moisture, and drying the sheet to increase its tensile strength sufficiently to run on the felts and over to the steam heated driers.

These suction rolls may be applied to the couch of Fourdrinier machines or used under the first and second presses, or on a board machine.

Prior art practice of paper makers required maintenance of a vacuum approximating ten inches of mercury in the interior of the suction roll box. As the speeds of paper machinery increased, with developments in the art, it became necessary to raise the vacuum on the suction rolls, often as high as eighteen to twenty inches of vacuum being maintained. It is now being proposed to increase the vacuum on the rolls to as high as twenty-five inches. It also was customary in the past to use a single box in the suction roll, later developments, however, including the installation in a few instances of dual-acting boxes.

With the higher vacuums has come a greatly increased problem of leakage, as obviously any air that leaks into a suction box has to be expanded from atmosphere up to the final vacuum. With this problem has come that of pump capacity limits.

The required pump capacity for a twenty-five inch vacuum as against that for a twenty inch vacuum would be in the ratio of the absolute pressures, or ten to five, that is the capacity of the vacuum pump will have to be twice as big to create and maintain a twenty-five inch vacuum as would be the case for twenty inches. It will thus be seen that it is very important to keep the leakage down to a minimum, especially where high vacuums are to be maintained, and a primary object of the present invention relates to an arrangement and means for effecting this purpose.

The air to be taken from the suction box, or suction roll, gets into the suction roll box from three principal sources; first, the amount of air passing through the sheet or paper web; second,

the amount of air carried in by the holes in the suction roll, and third, leakage between the packing and the shell. So far as known, no successful device, has heretofore been made to seal the packing, and an object of this invention is to provide adequate sealing of the suction box.

To this end the customary suction roll box is completely surrounded by an outer box, in which an intermediate vacuum is maintained. A large part of the air and water may, therefore, be removed by a pump at a relatively low vacuum, reducing by considerable amount the quantity of air to be removed at the higher vacuum. This makes possible maintenance of higher vacuum in the suction roll with smaller high vacuum equipment, and less power.

As exemplary, it may be assumed that a vacuum of twenty-five inches is to be created and maintained in the inner or main suction box, and twenty inches will be maintained as an intermediate vacuum in the outer box; or stated in other words, an absolute pressure of five inches on the inner box, and an absolute pressure of ten inches on the outer box.

The leakage past the packing may be regarded as an orifice where a fluid is flowing from high pressure on one side to a low pressure on the other. The flow through such an orifice will be in proportion to the square root of the density, and to the square root of the difference of pressure between the two sides of the orifice, up to a critical ratio, which in the case of a vacuum pump occurs at about fifteen or sixteen inches of vacuum.

If a single box were used, in the example given, where twenty-five inches is to be maintained, the leakage past the packing would be at a differential of twenty-five inches and the density would be that of atmosphere. But in the case of the double box, where twenty-five inches is maintained in the inner chamber and twenty inches in the outer or sealing chamber, the differential across the inner chamber will be from twenty to twenty-five inches, or a differential of five inches, and the density will be that of the twenty inch vacuum. Thus the comparative leakage will be, first, as the square root of the densities 30/10, or the square root of 3, and as the square root of 15/5, the ratio of the differential pressures, which in the case of the single box is taken at fifteen inches, as no more pounds of air will flow at twenty-five inches than at about fifteen inches differential. The square root of three times the square root of 3, equals 3, and hence it will be obvious that leak-

age is reduced to about one-third by the use of a double box.

Another advantage is that packing can be run longer without renewing, as leakage between the packing and the roll is not so important with this structure.

Still another object contemplates increasing the efficiency of such apparatus by the maintenance of higher vacuums than heretofore thought practicable, by minimizing introduction of air into the suction box.

A further object contemplates a structural arrangement which permits the use of lighter, smaller capacity pumping apparatus than would be possible in the case of high vacuums in a single box, as heretofore known.

While double or two-stage boxes have been utilized, as above stated, to assist in the creation and maintenance of high vacuum, so far as is known, no one has attempted to seal both sides of a suction box with an intermediate vacuum, and, accordingly, it is still another object of the present invention to supply such a seal, regardless of the number of stages used.

It may also be found more efficient to use two-stage pumping means, and the double box makes staging commercially practical. Accordingly, another and very important object includes a pumping arrangement in which the pumps are staged in such a manner that one pump may be used both for producing the intermediate vacuum in a low vacuum chamber, and as a second stage pump, for the high vacuum chamber.

To the attainment of the foregoing and other objects which will appear as the description proceeds, reference may be made to the accompanying sheets of drawings, in which—

Fig. 1 is a longitudinal section through the suction roll, taken on the line 1—1 of Fig. 3, and illustrating an arrangement of pumping equipment, with certain elements removed for clarification;

Fig. 2 is an end elevation of the suction roll, partly in section on the line 2—2 of Fig. 1, with certain elements removed for clarification;

Fig. 3 is a cross section through the suction roll taken on the line 3—3 of Fig. 1, and showing the double sealed box, with certain elements removed for clarification;

Fig. 4 is a top plan view of the suction boxes, with the suction roll removed;

Fig. 5 is a section on the line 5—5 of Fig. 4;

Fig. 6 is a section on the line 6—6 of Fig. 4; and

Fig. 7 is an enlarged fragmentary view of the upper left portion of Fig. 1 showing detail of end seal structure.

Referring now to the drawings, in which like reference numerals designate like parts, the suction roll comprises the metal shell or drum 10, preferably of bronze, and perforated throughout, as indicated at 11. The drum may be mounted in bearings 12 and driven by a suitable gearing 13 in a conventional manner. A wire or felt (not shown) in the form of an endless belt runs on the drum 10, carrying the wet paper pulp web or board. Within the suction roll is mounted a stationary suction box 14, supported on suitable trunnions, and held in contact with the operating surface of the suction roll by springs 15, and the vacuum. The roll and box will, of course, be mounted in the usual supporting frame 16.

Suitable packing strips 17 and 18 aid in reducing leakage between the suction roll 10 and

the interior of the box 14, and screws 19 provide an adjustment to prevent excessive wear on the packing strips. Adjustable plugs 20 may be provided as a means of accommodating the working surface of the box to the width of the paper web running through the machine.

The box 14 is divided into two chambers 21 and 22. The chamber 22 which surrounds the chamber 21, is connected to a vacuum pump by a suitable pipe or conduit 24, and the pump 23 will serve to maintain an intermediate vacuum, for example, of twenty inches, in the box 22.

The chamber 21 is connected to a vacuum pump 25 by a conduit 26, and this pump is operated to produce a considerably higher vacuum than pump 23, and will be effective to create and maintain, for example, twenty-five inches of vacuum. The discharge of pump 25 may be either to atmosphere through conduits 27 and 28, or into the pipe or conduit 24 to the intake of pump 23. Suitable controlling valves 29 and 30 may be regulated to determine the discharge.

The pump 23 discharges to the atmosphere through an exhaust conduit 31, and may utilize a separating tank 32, as shown in Fig. 1, whereby the bulk of the liquid brought over from the suction roll can be removed under a vacuum, either by a pump 33, or by a suitable water leg.

Prime movers, such as motors 34 and 35 are used to drive the pumps 23 and 25, respectively.

Having thus described the invention, the operation thereof will be readily apparent. The revolving suction roll carries the web of wet pulp, or partially formed paper on the Fourdrinier wires, or felts, over the chambers 21 and 22 in the suction box 14, and the vacuum in these chambers removes the water, and partially dries the web, after which the web passes over to the driers. With the double box as described, it is possible to carry a higher vacuum than heretofore. The paper is subjected to a longer contact and greater air pressure than would be possible with a single box. This makes a harder, drier sheet, which will be less liable to break. The paper machine can be run faster, and less steam will be required for drying.

Smaller pumping equipment can be used, due to the dual vacuum conditions within the roll, with attendant minimum leakage, and the pumping mechanism can be staged, utilizing the pump 23 to produce the vacuum in the chamber 22 and as a second stage pump for the high vacuum pump 25.

It is quite clear from the foregoing that the primary purpose of the invention is to seal the main suction box against leakage at all points where same might occur, regardless of whether there be one, two, or more of such points, and to do this by vacuum means. Since the points may be different with different structures, and may vary in number as well as location, it will be evident that many variations and modifications in structure effective to produce the desired result will readily occur to those skilled in the art.

For example, if it is desired to seal the ends of the chamber 21 by vacuum from within the chamber 22, the adjustable plugs 20 may be cut away to provide channels or recesses 36 (Figs. 4, 5 and 6), and tapped or formed with conduits 37 extending from one side of the respective packing strips 18 to the other. Obviously then, any leakage past the packing strips 17 into the recess or cut-out channel 36 will be carried into the region of lower vacuum in the chamber 22, thus sealing the main chamber 21.

Again, while a two-stage box is illustrated, it is obvious that more than two stages could be used if desired, and there may be other changes which would be well within the scope of this invention. It follows then that the disclosures herein shall be construed as illustrative, and not as limiting except as defined in the appended claims.

I claim:

1. A suction box for the suction roll of a paper making machine comprising a chamber effective to maintain a predetermined vacuum on the roll, and means to seal said chamber against leakage comprising a second chamber surrounding said first chamber and effective to maintain and place a sealing vacuum for said first chamber on the roll independently of said first chamber, and means for independently creating a vacuum within each of said chambers.

2. A suction box for the suction roll of a paper making machine comprising a chamber effective to maintain a predetermined vacuum on the roll, and means to seal said chamber against leakage comprising a second chamber surrounding said first chamber and effective to maintain and place a sealing vacuum for said first chamber on the roll independently of said first chamber, and means to create a vacuum of predetermined degree in said first chamber, and means to create a vacuum of a different predetermined degree in said second chamber.

3. A suction box for the suction roll of a paper making machine comprising a chamber effective to maintain a predetermined vacuum on the roll, and a second chamber surrounding said first chamber and effective to maintain and place a vacuum on the roll independently of said first chamber, means to create a vacuum of predetermined degree in said first chamber, means to create a vacuum of a different predetermined degree in said second chamber, and selective means to operatively connect said vacuum creating means together, whereby said second vacuum creating means will operate as a second stage to said first vacuum creating means.

4. In a paper making machine, the combination of a suction roll, a double suction box therefor comprising two separated, non-communicating chambers each communicating independently with said roll, pumping means connected to one of said chambers and effective to produce and maintain a vacuum therein, a second pumping means connected to said second chamber and effective independently to produce and maintain a vacuum therein, said chambers being so related that the vacuum in one of said chambers will seal the other of said chambers at all points of leakage.

5. In a paper making machine, the combination of a suction roll, a double suction box therefor comprising two separated, non-communicating chambers each communicating independently with said roll, pumping means connected to one of said chambers and effective to produce and maintain a vacuum therein, a second pumping means connected to said second chamber and effective independently to produce and maintain a vacuum therein, said chambers being so disposed relative to each other that the vacuum in one of said chambers will seal the other at all points of leakage and means to interconnect said

pumping means whereby one of said pumping means in addition to its normal operation will supplement the pumping action of the other of said pumping means.

6. The combination with a suction roll, of a suction box having a low vacuum chamber and a high vacuum chamber, each effective to maintain and place a vacuum on the roll, independently of the other a pump for creating and maintaining a vacuum in said high vacuum chamber, and a second pump for producing a lower vacuum in the low vacuum chamber, said low vacuum chamber being so positioned relative to said high vacuum chamber as to seal said vacuum chamber at all points of leakage.

7. The combination with a suction roll, of a suction box having a low vacuum chamber and a high vacuum chamber, each effective to maintain and place a vacuum on the roll, independently of the other a pump for creating and maintaining a vacuum in said high vacuum chamber, and means to seal said high vacuum chamber at all points of leakage including a second pump for producing a lower, sealing vacuum in the low vacuum chamber, said second pump being connected to said first pump as a second stage pump therefor.

8. In a paper making machine, the combination with a suction roll, of a suction box effective to maintain a vacuum on that portion of the roll over which the paper web passes, and a second suction box independent of said first suction box and disposed relative to said first box as to seal said first suction box at all points of leakage, and separate means to exhaust said suction boxes independently of each other.

9. In a paper making machine, the combination with a suction roll, of a suction box effective to maintain a vacuum on that portion of the roll over which the paper web passes, and a second suction box independent of said first suction box and disposed relative to said first box as to seal said first suction box at all points of leakage, and means to maintain a lesser degree of vacuum in said second suction box than that maintained in the first suction box, independently of said first suction box.

10. A suction box for the suction roll of a paper making machine comprising a chamber effective to maintain a predetermined vacuum on the roll, and means to seal said chamber against leakage comprising a second chamber surrounding said first chamber and effective to maintain and place a sealing vacuum for said first chamber on the roll independently of said first chamber, means to create a vacuum of predetermined degree in said first chamber, means to create a vacuum of a different predetermined degree in said second chamber, and selective means to operatively connect said vacuum creating means together, whereby said second vacuum creating means will operate as a second stage to said first vacuum creating means.

11. The method of sealing the suction box of a suction roll in a paper making machine against leakage, which comprises creating and maintaining a vacuum of lesser degree than that within said suction box, independently and separately of the vacuum within said suction box, applying the vacuum so produced to all points of leakage exteriorly of said box, and maintaining relative in-communicativeness between said vacuums.

IRVING C. JENNINGS.
